UNITED STATES PATENT OFFICE.

STACY C. THOMPSON, OF MANISTEE, MICHIGAN, ASSIGNOR OF ONE-FOURTH
TO JOHN A. THOMPSON, OF SAME PLACE.

ADDRESSING-MACHINE.

SPECIFICATION forming part of Letters Patent No. 376,762, dated January 24, 1888.

Application filed June 9, 1887. Serial No. 240,735. (No model.)

To all whom it may concern:

Be it known that I, STACY C. THOMPSON, a citizen of the United States, residing at Manistee, in the county of Manistee and State of Michigan, have invented certain new and useful Improvements in Addressing-Machines; and I do hereby declare the following to be a full, clear, and exact description of the invention, such as will enable others skilled in the art to which it appertains to make and use the same.

My invention relates, generally, to addressing or mailing machines, and more particularly to that class of mailing-machines which are attached to printing-presses and automatically operated therefrom; and it consists in the construction and combination of parts, which will be hereinafter disclosed in the description and claims.

The object of my invention is to provide an improved addressing or mailing machine, which is attached to and operated by a newspaper or other printing machine, whereby the names and addresses of subscribers are separately printed on the papers before the latter leave the machine. I attain this object by the mechanism hereinafter described, and shown in the accompanying drawings, wherein the same reference-numerals indicate the same or corresponding parts, and in which—

Figure 1 represents a plan view of a part of a printing-press having my improved addressing or mailing machine attached thereto. Fig. 2 represents an end elevation of the same. Fig. 3 represents a front elevation of my improved mailing-machine, partly in section and partly broken away. Fig. 4 is an end elevation of the same. Fig. 5 is a detail broken longitudinal section of a galley. Fig. 6 is an end view of the same.

In the drawings, 1 represents a printing-press of any ordinary construction, to which my improved addressing or mailing machine is attached.

2 is the main shaft of the press, which imparts motion to the printing-cylinder and also to the eccentric mounted on the outer end thereof, which operates a part of the addressing or mailing machine.

3 is a sleeve mounted upon the outer end of said main shaft and suitably secured thereto.

This sleeve has a lug, 4, formed integrally therewith, which operates in connection with the eccentric 5, having a similar lug, 6. The purpose of these lugs will be hereinafter stated. 55 The eccentric is mounted and revolves upon the periphery of the sleeve 3.

7 is the eccentric-rod, which is connected to and operates the rack mechanism for moving the galleys, as hereinafter described. 6c

8 is a sprocket-chain which passes around two sprocket-wheels of like diameters, one of which (not shown) is secured to the inner side of the eccentric 5 and revolves with it, and the other, 9, is mounted upon and operates the 65 shaft upon which is mounted the hammer-cam and hammer, as hereinafter described.

10 is a metallic guide-plate and cover for the addressing-machine, as shown in Figs. 1, 2, and 3. It extends out from the side of the addressing-machine which is next the press and bends down, so that the edge of the paper, as it comes from the press, strikes the same and is forced upward, so as to be carried between the tapes, hereinafter described, and over the addressing-machine. This plate and cover also prevents bagging or sagging of the paper while passing between the tapes, and keeps the same from coming in contact with the inked names and addresses in the addressing-machine and protects the type. An opening, 23, is formed in said guide-plate and cover at the point where the hammer strikes, and is of sufficient size to permit the face of said hammer to pass through it and come in contact with the type in the 85 galley as they pass beneath said guide-plate. 7c 80

11 represent two sets of tapes, arranged one above the other, and operating to convey the paper between them from the press to the addressing-machine. I use two sets of tapes, 90 as illustrated in Fig. 2, for a double purpose: first, they carry the paper accurately and positively from the printing-cylinder to the addressing-machine, and, second, they prevent sudden gusts of wind from disarranging the 95 paper before reaching the addressing-machine.

12 are the tape-pulleys, mounted upon revolving shafts, as shown.

13 is a shaft which is suitably journaled in the uprights 13, secured at the ends of the 100 frame of the machine. Upon this shaft are mounted the hammer-cam 14 and the hanger

17, which supports the hammer-arm 15 and impression-hammer 16. This shaft is revolved by means of the sprocket-wheel 9, mounted on the end thereof, and the sprocket-chain 8. The 5 hammer-cam is rigidly secured to this shaft, revolves with it, and is provided with a depression, 19, in its periphery, as shown in Fig. 4, into which enters, as said cam revolves, a small roller, 18, which is pivotally attached 10 to the side of the outer end of the hammer-arm 15. This arm 15 has attached to it the intermittently-operated impression-hammer 16, and is pivotally attached to the bifurcated hanger 17, which is loosely mounted on the 15 shaft 13, and held from vibrating or oscillating by a stay-rod or bracket, 15', attached to the frame-work of the press, as shown in Fig. 4. The impression-hammer 16 is adjustably attached to the hammer-arm 15, and its face, 20 or that portion which comes in contact with the type and makes the impression, is covered with felt, rubber, cloth, or other pliable or yielding material, so as to prevent the type from being mashed or otherwise injured from 25 the stroke of the hammer. The head of the hammer is made heavy, so as to act as a weight, and thus facilitate its downward movement; also, said head is bifurcated or slotted where the hammer-arm is attached thereto, and said 30 arm is secured therein by means of a set-screw, as shown in Fig. 4. By this construction and arrangement of parts the hammer can be lowered or raised, so as to make a heavy or light impression, as may be desired. The small 35 pivoted roller is mounted on the inner side of the outer end of the hammer-arm 15 in such a manner as to allow it to travel upon the periphery of the cam 14 when the latter is in motion. When the cam revolves in the direction indicated by the arrow in Fig. 4, the 40 roller 18 moves out of the depression 19 and causes the hammer-arm and hammer to assume the position indicated by the dotted lines; but as soon as said depression is again 45 reached said roller suddenly enters therein, releases the hammer-arm, and allows the hammer to drop down upon the type and thus make an impression. As the shaft 13, upon which the hammer-cam is mounted, receives its motion from the sprocket-wheel 9, the sprocket-chain 8 and the sprocket-wheel, (not shown,) which is secured to the inner side of the eccentric 5, as heretofore described, and as these sprocket-wheels are of the same diameter, each 50 revolution of the driving-shaft 2 causes the cam 14 to make a like revolution and operate the hammer to effect an impression or address upon each passing newspaper or sheet. Of course, in order to effect this, the hammer is 55 intermittently operated.

20 20 represent the galley upon which are placed the type for printing the names and addresses of subscribers, &c., and which are constructed in suitable lengths and widths, as 60 may be desired. On the under sides of the same are formed or secured teeth or cogs, arranged as shown in Figs. 5 and 6, and meshing

with cogs of similar construction on the rack-lever 22. The lines of type containing the names and addresses on the galley are arranged 70 equidistant and correspond in distance apart to the spaces between the cogs on the under side of said galley. The ends of the galley are constructed of thin metal strips 20", so that when one end of one galley is placed against 75 the end of another the meeting end pieces will be located immediately above one of the cogs upon the under side of the lower scarfed end of the galley, and will both together occupy the space of and register with said cog. 80 The object of these narrow ends to the galley is that the space between the end names on said galley, when the latter are placed end to end, may not be more than the space between the names on other portions of the galley. 85 This will permit the galley to follow closely after each other, and the names and addresses to be as uniformly arranged as if they were all contained in one galley, and at the same time the possibility of skipping a name and address 90 between galley will be prevented. The ends of the galley are also provided with scarfs 20² and 20³, as shown in Fig. 5, by which they are removably locked or hooked together, the scarf 20³ of one being placed in scarf 20² of 95 another, thus forming a practically-continuous galley of any desired length.

21 21 are the slideways upon which the galley are placed and moved along by the rack-lever 22. These slideways are suitably attached to the sides of the frame of the machine, as shown in Figs. 3 and 4.

The rack mechanism for operating the galley is partly arranged beneath the opening 23 in the guide plate or cover 10, and consists 105 of the rack-lever 22, having the form of a bell-crank, and the cross head 28, as clearly shown in Fig. 3 of the drawings. On the upper surface of the short arm of said rack-lever cogs 25 are provided, which are made to mesh 110 with the cogs on the under sides of the galley. The rack-lever 22 is pivoted at 26 to upwardly-extending lugs 27 of the cross-head 28, which is formed, as shown in Fig. 3, with a slot passing through its bottom, and between the lugs 115 27, through which the long arm of the rack-lever 22 passes, as shown in Fig. 3. This cross-head is supported by and moved in suitable slideways, 30, attached to the frame of the machine. The long arm of the rack-lever 22 is 120 slotted at its lower end, as shown at 31, to which the rod 32 is pivotally attached at one end, the other end being similarly attached to a bell-crank lever, 33. This bell-crank lever has a long arm, 34, and a short arm, 35, which 125 are provided with slots 36 and 37, respectively, for adjusting the rod 32 and the eccentric-rod 7, the latter being pivoted in slot 36, as shown in Fig. 1. By the adjustment of said eccentric-rod 7 and the rod 32 in the slots 36 and 37 of the bell-crank lever, the feed movement 130 of the galley is regulated so as to cause them to move one, two, or more spaces or cogs at a time, as may be required. The bell-crank

lever 33 is pivoted at 38 to the frame of the machine, as illustrated in Fig. 1.

The manner in which the galley is operated by the rack mechanism is as follows:

5 When the main or driving shaft 2 of the press revolves, the lug 4 of the sleeve 3 comes in contact with the lug 6 of the eccentric 5 and causes the latter to revolve upon the sleeve 3 and impart to the eccentric-rod 7 a backward-and-forward motion, in the usual manner. As the eccentric-rod is drawn back or in the direction indicated by the arrow in Fig. 2 it draws the long arm 34 of the bell-crank lever 33 in the same direction, and causes the rod 32, which is secured to the short arm 35 of said lever, to move horizontally, and consequently the long arm of the rack-lever 22 is made to assume the position indicated by the dotted lines in Fig. 3, the lever 22 having come in contact with the 15 end of the slot in the cross-head. By this movement of the rack-lever the cogs thereon are disengaged from the cogs on the bottom of the galley, and as the rod 32 and the eccentric-rod 7 are still further drawn backward by the eccentric the rack-lever and cross-head slide backward for a distance just equal to the thickness of a cog on the galley. As soon as the eccentric has completed its revolution the eccentric-rod 7, bell-crank lever 33, rod 32, and 20 the rack-lever 22 begin their motion in the opposite direction, which causes the cogs on the rack-lever to rise and again mesh with the cogs on the bottom of the galley, the lever 22 coming in contact with the end of the slot in 25 the cross-head opposite the end above referred to, and as the motion is further extended the rack-lever and cross-head slide forward to their former positions and cause the galley to move forward. In this operation of the rack mechanism the cogs or teeth on the rack-lever mesh with the cogs on the bottom of the galley, force the latter along the necessary distance to present a different name and address beneath the opening in the plate and cover, then drop out 30 of mesh, move back, then move up again into mesh with the cogs on the galley and force the latter along, and so continue until the end of the galley is reached. As every movement of the galley is simultaneous with every revolution of the press-cylinder by reason of the eccentric being mounted on the driving-shaft thereof, for each newspaper that is printed by a revolution of the cylinder the galley is moved along just the space of one name and address 35 directly beneath the opening 23 in the guide-plate and cover 10, and receives a stroke from the impression-hammer 16, which is operated as hereinbefore described.

A small bell, 39, is arranged on the under side of the addressing-machine beneath the galley, and is so set as to sound an alarm when a galley containing a given number of names and addresses has passed beneath the opening 23 and it is time to remove one galley from 40 and place another in the machine. This bell is sounded by a pivoted lever, 39', which is

attached to the frame and rests against the bottom or under side of the galley, and by a pivoted arm, 39", connected to the lower end of said lever 39' and provided with a hammer, 70 39", at its lower end. When the end of a galley has been reached and it passes off the lever 39', the latter suddenly rises and causes the arm 39" or its hammer to strike against the bell, and thus notify the pressman. This bell 75 may be placed under the machine at any point, and may also be so set as to sound an alarm when any given number of names and addresses have not yet passed under the impression-hammer. It does away with the constant 80 watching of the machine.

The manner in which names and addresses are applied to papers as soon as printed is as follows: The papers are fed to the press and printed in the usual manner. After leaving 85 the press each paper is conveyed between the tapes 11 and over the guide-plate 10, and as it passes the opening 23 in said guide-plate between the type and the impression-hammer the latter descends and presses the paper 90 against the type, and thus effects the desired impression. If from any cause a sheet of paper should become disarranged or fail to be fed to the tapes in proper order, the pressman can stop and reverse the cylinder for nearly a 95 whole revolution, or until the lug 4 of the sleeve 3 comes in contact with lug 6 of the eccentric, and then readjust said sheet or substitute another paper without allowing a single name and address in the galley to pass 100 without receiving an impression.

Having thus fully described my invention, what I claim as new is—

1. In an addressing-machine, the combination of a movable galley having cogs or teeth 105 on its under surface, the slideways, the cross-head, the rack-lever having cogs or teeth on the upper surface of its horizontal arm, and means, substantially as described, for intermittently moving said lever from the printing-press, substantially as described.

2. In an addressing-machine, the combination of the movable galley 20, having cogs or teeth, the slideways 21, the slotted cross-head 28, the slideways 30, the rack-lever 22, having cogs or teeth, the rod 32, the slotted bell-crank lever 33, and means, substantially as described, for operating the same, substantially as described.

3. In an addressing-machine, the combination of the movable galley 20, having cogs or teeth, the slideways 21, the slotted cross-head 28, the slideways 30, the rack-lever 22, having cogs or teeth, the rod 32, the slotted bell-crank lever 33, eccentric-rod 7, and eccentric 125 5, substantially as described.

4. The combination, in a printing-machine having a main shaft provided with an eccentric formed with a lug, and with a sleeve, also formed with a lug, of an addressing-machine 130 provided with a movable galley, and operating mechanism, substantially as described, inter-

mediate of said eccentric and said movable galley, substantially as described.

5. The combination of two or more movable galleys provided with scarf'd ends for removably holding or locking them together, with means, substantially as described, for supporting and operating said galleys, substantially as described.

6. In an addressing-machine, the combination of two or more galleys having teeth or cogs upon their under sides, and having end pieces formed of thin metallic strips registering, when brought together, with one cog upon the under side and occupying the space of the 15 said cog, substantially as and for the purpose described.

7. The combination, with the main shaft of the printing-press, the sprocket-wheels, the sprocket-chain, the shaft carrying the cam, 20 and the impression-hammer, of the galley and mechanism, substantially as described, for intermittently moving the same, substantially as described.

8. The combination, with the intermittently-moving galley and the guide-plate and cover for the same, provided with the opening, 25 of the intermittently-operated impression-hammer, substantially as described.

9. The combination of the printing-press and addressing-machine with two intermediate sets of tapes, one set being arranged above the other, substantially as and for the purposes described.

10. The combination of the printing-press, two sets of tapes, one set being arranged above 35 the other, and shafts and pulleys for operating the same, with an addressing-machine having a cover and guide-plate, a movable galley, and means, substantially as described, for moving the same, substantially as de- 40 scribed.

11. The combination, with a movable galley, of a pivoted lever normally resting against the bottom of said galley, a pivoted arm attached to the lower end of said lever and having a hammer at its upper end, and a bell which is sounded by said hammer, substantially as and 45 for the purpose described.

In testimony whereof I affix my signature in presence of two witnesses.

STACY C. THOMPSON.
